Application September 16, 1949, Serial No. 5,041

Term of patent 14 years

(Cl. D15—1)

To all whom it may concern:

Be it known that we, Jane E. Voelker, a citizen of the United States of America, residing at New Salem, in the county of Franklin in the State of Massachusetts, Edward M. Voelker, a citizen of the United States of America, residing at New Salem, in the county of Franklin in the State of Massachusetts, and John W. Sabbagh, a citizen of the United States of America, residing at Jackson Heights, L. I., in the county of Queens and State of New York, have invented a new, original, and ornamental Design for a Chair, of which the following is a specification, reference being had to the accompanying drawing, forming part thereof.

Figure 1 is a three-quarter front-side perspective view of a chair showing our new design, both sides of the chair being the same.

We claim:

The ornamental design for a chair, as shown and described.

JANE E. VOELKER.

EDWARD MORGAN VOELKER.

JOHN W. SABBAGH.
